P. A. HIRSCH

PULVERIZER

Filed July 3, 1922

UNITED STATES PATENT OFFICE.

PAUL ARTHUR HIRSCH, OF ERIE, PENNSYLVANIA, ASSIGNOR TO FURNACE ENGINEERING COMPANY, OF NEW YORK, N. Y., A CORPORATION OF NEW YORK.

PULVERIZER.

Application filed July 3, 1922. Serial No. 572,531.

To all whom it may concern:

Be it known that I, PAUL A. HIRSCH, a citizen of Great Britain, residing at Erie, in the county of Erie and State of Pennsylvania, have invented new and useful Improvements in Pulverizers, of which the following is a specification.

This invention is an improvement in pulverizers, that is, machines for pulverizing coal, ores, etc. This invention is particularly designed for pulverizers which are used for pulverizing fuel and delivering it directly to a furnace for consumption. With such pulverizers there is usually a

18 draft of air.

The invention is shown applied to the general type of pulverizing apparatus illustrated by the patent of Storer 254,403 of February 28, 1882, in which there is a 20 rotary shaft at the center of a fixed cylindrical casing, and a succession of chambers within the casing, beaters or blades carried by the shaft and operating in the respective chambers to reduce the material progressively, with obstructing annular walls between the chambers tending to hold back any large or heavy particles, and with air and fuel admission at the first end, and a fan in the final chamber operating to 30 create air flow and to discharge the air and pulverized material, with regulable admission of additional air near the fan. In a prior Patent No. 1,453,977 I suggested certain variations from Storer's apparatus, namely, 35 providing in the second or pulverizing chamber a drum rotating with the shaft and of such diameter as to form a relatively narrow annular passage confining the whirling air and fuel, and arranging the pulverizing 40 blades at a slant on the drum so as to accelerate the flow toward the usual fan near the discharge; also introducing a mesh screen in the annular wall between the first or crushing chamber and the second chamber 45 to obstruct more effectively the passage of foreign material, such as bits of metal from the first chamber. These features I no longer employ, but resort to Storer's basic form and modify the same along independent lines.

The general objects of the present invention are to secure a more efficient and satisfactory pulverizing machine; to secure a more uniform and thorough pulverization, 55 giving a product of finer quality; to prevent

the delivery of particles not completely pulverized, to increase speed and output and enable reduction of floor space; and to afford a machine of better durability and life.

Other features and details will appear from the specification and claims.

To the accomplishment of the stated objects and advantages, the present invention consists in the novel pulverizing machine 65 herein illustrated and described, and the novel features of combination, construction and detail as hereinafter referred to.

The invention is illustrated in the accompanying drawings as follows:

Fig. 1 shows a side elevation, partly in radial section.

Fig. 2 a section on the line 2—2 in Fig. 1,
Fig. 3 a section on the line 3—3 in Fig. 1,
Fig. 4 a section on the line 4—4 in Fig. 1.

1 marks the base, 2 posts extending upwardly from the base, 3 an operating shaft journaled in bearings 2^a in the posts 2, and carrying a driving means or pulley 3^a, 4 represents a drum having linings 4^a enclosing the respective reducing chambers, 5 posts carrying the drum, 6 a breaker chamber in which the coal is first crushed, and 7 and 7^a pulverizing chambers as they are usually called in machines of this type.

Fuel is introduced in the hopper 8 and passes through an opening 8^a to the breaker chamber 6. The breaker chamber comprises breaker paddles 9 which are secured to a disc 10, the disc being secured to a hub 11 fixed on the shaft 3.

Pulverizer beaters are arranged in the chamber 7, these having the beater paddles 12 secured to discs 13. The discs are secured to hubs 14 which are fixed on the shaft 3. A beater comprising paddles 15 are arranged in the chamber 7^a, the paddles being secured to a disc 16, the disc being secured to a hub 17 fixed on the shaft 3. A discharge opening 18 leads from the pulverizer chamber 7^a to a fan chamber 19 in which there is arranged a fan 20, the fan discharging through an opening 21. Supplemental air is delivered to the fan chamber through an opening 22 in the end of the drum. This opening may be controlled by a shutter 23 controlled by a screw 24.

A plate 25 forms a restricting device between the breaker chamber 6 and the chamber 7. This restricting plate or partition

makes the opening 26 between the breaker chamber and pulverizing chamber of less diameter preferably than the inner edge of the paddles 9 and of a less diameter than the diameter of the disc 10 and disc 13.

In order to obstruct the rotary movement of the material I provide preferably between the chambers 7 and 7^a radially and axially arranged blades 27 which prevent a movement of the material in a whirling or circumferential direction passing from one chamber to the other. I provide similar blades 28 between the chamber 7^a and the fan chamber, in fact the blades 28 are the more important in that it is only necessary to prevent the final discharge of the fuel in an unpulverized state.

While I have shown the blades extending in a direct radial direction I do not wish to be understood as being limited to blades which extend accurately in a radial direction as this may be varied as desired. They need not be straight and may extend from the periphery entirely to the shaft or somewhat short of it. They may be welded or otherwise attached at their outer ends to the elements 4^a, 29 or 30, and may have their inner ends steadied by a short sleeve as shown.

The chief feature of novelty of the present invention is the introduction of the whirl obstructing members, vanes or spokes, located in advance of the fan, but beyond one or more of the reducing devices, serving to prevent, obstruct or substantially eliminate the whirling motion, and compel a generally axial motion of the air and carried matters for the lineal extent of the whirl obstructing elements. Referring, for example, to the whirl obstructing elements or vanes 28 beyond the last of the pulverizing chambers or spaces and in advance of the fan, these perform a very important function. They are preferably fixed with relation to the outer casing, and are so shown, although the principle of operation would not be changed if they were permitted to rotate in a slow manner or reverse direction, in view of the tremendously high speed of the pulverizing elements. In their preferred form the whirl obstructing elements are vanes, spokes, plates or bars, and having substantial extent in an axial direction, so that the whirling air and carried materials, in order to pass from the pulverizing chamber to the fan chamber, must cease whirling as they traverse the non-central axially extending passages existing between the obstructing vanes or strips. The precise form and disposition of the whirl obstructing vanes 28 are not important so long as they afford these non-concentric passages between two chambers and of sufficient axial extent to prevent whirling; they may be arranged as spokes

in straight radial lines as indicated in Fig. 3, or otherwise, and their longitudinal direction may be parallel to the axis as shown, or otherwise. In operation the gases whirling at high speed are suddenly compelled to adapt themselves to the conditions created

70 by the whirl obstructing elements, the whirling rotation substantially ceasing the air passing forward to the next chamber, and the particles of material in the air striking the lateral surfaces of the vanes with very high impact, giving an extremely effective and fine degree of pulverization. Indeed a great part of the pulverizing duty is taken by these stationary vanes, and to a large extent the rotary beaters or paddles are relieved of the duty, thus giving greater durability to them and longer life to the apparatus. The amount of pulverizing action 85 taking place in my apparatus is greatly increased by this improvement, and the pulverizing rendered far more thorough. Finely pulverized matters will pass forwardly with the air to the fan chamber, but it is believed that any substantial particles which are not thoroughly reduced in the described impact are caught in a reverse swirl and blown back into the pulverizing chamber, to be again subjected to the action therein and to further impact upon the whirl obstructing elements, giving maximum reduction 90 before any material can pass into the fan chamber and be discharged. The principles described apply also to the whirl obstructors 27 between two of the reducing chambers, and in addition is afforded further pulverizing action by the fact that the gases enter the second chamber in non-whirling condition and are compelled to be speeded up by the reducing elements, giving increased beating impact at this point.

The features thus described are well adapted to increased speeds of rotation. Indeed the higher the speed the more effective the operation of this improvement. With 110 increase of speed the number of crushing and pulverizing elements can be reduced, so that a much smaller apparatus can be made, occupying less floor space, operating at high speed, delivering increased quantities of 115 pulverized fuel, and with a greater degree of fineness of pulverization.

The herein described structure may be supplemented in many ways by details and refinements which suggest themselves or are suggested by prior structures. For example, between the first and second pulverizing chambers 7 and 7^a may be arranged annular plates 29 restricting the diameter 120 of the outlet or passage 18 from one chamber to the next. Structurally these may be combined with the obstructing vanes 27. Similarly in the passage 18^a from the final chamber 7^a to the fan may be annular plates 30 125 adjacent to the obstructing vanes or blades 130

28. Circumferentially outside of the reducing elements may be provided fixed ribs 31 cooperating in the reducing action, as seen in the lower part of Fig. 2, where 5 they are indicated as attached to one of the linings 4.

Since many matters of combination, arrangement, design, structure and detail may be variously modified without departing 10 from the principals hereof it is not intended to limit the invention to such matters except so far as specified in the appended claims.

What I claim as new is:—

15 1. In a pulverizer, the combination of a pulverizer chamber having an axial discharge from the chamber; rotary beaters in the chamber; and wide thin vanes arranged for obstructing a rotary movement 20 of the material during its discharge from the chamber without at the same time materially increasing the axial speed of flow.

2. In a pulverizer, the combination of a pulverizer chamber having an axial discharge from the chamber; rotary beaters 25 in the chamber; and means obstructing a rotary movement of the material during its discharge from the chamber comprising a number of spaced apart blade-like vanes 30 arranged not to materially obstruct axial flow.

3. In a pulverizer, the combination of a pulverizer chamber having an axial discharge from the chamber; rotary beaters 35 in the chamber; and means obstructing a rotary movement of the material during its discharge from the chamber comprising relatively stationary blade-like vanes arranged substantially axially and spaced 40 apart to form flow spaces between them of greater area than the sections of the blades.

4. In a pulverizer, the combination of a pulverizer chamber; a plurality of rotary beaters arranged in the chamber; and 45 means between the beaters obstructing a rotary movement of the material in passing from one beater to the other comprising a number of blade-like vanes set edgewise to the axial direction and of substantial 50 axial dimension.

5. In a pulverizer, the combination of a pulverizer chamber having an axial discharge; a plurality of rotary beaters spaced 55 apart axially in the chamber; means arranged in the chamber between the beaters obstructing a rotary movement of the material as it passes from one beater to the other; and means obstructing a rotary movement of the material during its discharge 60 from the chamber, said obstructing means comprising wide thin vanes arranged to give such obstruction without materially increasing the axial speed of flow.

6. In a pulverizing machine a casing con- 65 taining one or more reducing chambers, re-

ducing members in each chamber and means for rotating the same at high speed, and whirl obstructing elements at the discharge of a chamber comprising relatively thin vanes or blades arranged with substantial 70 axial dimension.

7. Machine as in claim 6 and wherein means are employed to cause air progress axially through the casing, and wherein the whirl obstructing elements are wide flat 75 vanes arranged to afford non-concentric axial passages in the discharge from a chamber.

8. In a pulverizing machine a casing containing one or more reducing chambers, re- 80 ducing members in each chamber and means for rotating the same at high speed, and whirl obstructing elements at the discharge of a chamber comprising wide thin vanes extending from substantially the center of 85 the casing to the periphery.

9. A pulverizing machine comprising a casing containing a succession of chambers or reducing spaces, a centrally arranged shaft adapted to high speed rotation, re- 90 ducing elements on said shaft operating in a plurality of said chambers, a fan chamber containing a fan and arranged to draw air from a reducing chamber, and whirl ob- 95 structing means between two adjacent re- 100 ducing chambers comprising elements of such small dimension transverse to the axial direction as not materially to speed up the axial flow, and of relatively large dimen- 105 sion in an axial direction.

10. A pulverizing machine comprising a casing containing a succession of chambers or reducing spaces, a centrally arranged substantially horizontal shaft therein adapt- 105 ed to high speed rotation, reducing elements on said shaft operating in a plurality of said chambers, a fan chamber containing a fan and arranged to draw air from a re- 110 ducing chamber, and whirl obstructing means between the fan chamber and an ad- 115 jacent reducing chamber.

11. A pulverizing machine comprising a casing containing a succession of chambers or reducing spaces, a substantially horizontal shaft therein adapted to high speed 115 rotation, reducing elements on said shaft operating in a plurality of said chambers, a fan chamber containing a fan and ar- 120 ranged to draw air from a reducing chamber, and whirl obstructing means between two adjacent reducing chambers, and be- 125 tween the fan chamber and an adjacent re- ducing chamber.

12. In a pulverizing machine a relatively 125 fixed drum, a rotatable shaft therein, reduc- ing paddles rotating with said shaft adapt- ed to impart rotary motion to the air and solid material therein, and a system of out- wardly extending elements arranged within the drum to obstruct the rotary motion of 130

- the matters passing between them without greatly accelerating the axial advance thereof. 55
13. Machine as in claim 12 and wherein the obstructing elements are a series of blade-like vanes set edgewise toward the axial flow and presenting spaces between them of far greater area than that of the vanes. 60
14. Machine as in claim 12 and wherein the obstructing elements are substantially flat and radial stationary blades extending from the drum substantially toward the shaft, with radially extending spaces between them. 65
15. In a pulverizing machine a casing or drum, means for causing axial progress of the air therethrough, rotatable reducing members or beaters in said casing, a whirl 70 obstructing chamber in said casing adjacent and beyond said reducing members, and means in said chamber for substantially obstructing rotary movement of the air without materially obstructing its axial progress. 75
16. Machine as in claim 15 and wherein is provided an annular wall at the outer portion of said whirl obstructing chamber and between it and the space or chamber in which the reducing members rotate. 80
17. Machine as in claim 15 and wherein is provided an annular wall at the outer portion of said whirl obstructing chamber and between it and the space or chamber in which the reducing members rotate, and another such annular wall between the whirl obstructing chamber and the space, there- 85
18. Machine as in claim 15 and wherein is provided an annular wall at the outer portion of said whirl obstructing chamber and between it and the space or chamber in which the reducing members rotate, and said whirl obstructing means consisting of blade-like vanes extending from near the center of the chamber outwardly to said annular wall. 90
19. In a pulverizing machine a casing, a high speed shaft rotatable therein, beating means rotating with said shaft, and a set of wide and thin blade-like vanes arranged substantially edgewise to the axial advance of the material in the casing to obstruct the whirling motion thereof after leaving the heating means. 95
20. In a pulverizing machine a casing, a high speed shaft rotatable therein, beating means rotating with said shaft, and whirl obstructing vanes, of surface width substantially not less than seven per cent of the interior diameter of the casing, arranged beyond the beating means. 100
21. In a pulverizing machine a casing, a high speed shaft rotatable therein, beating means rotating with said shaft, consisting of a set of paddles, and, beyond the space in which said paddles rotate, a set of whirl obstructing vanes. 105
22. Machine as in claim 21 and wherein such vanes are wide, thin blade-like structures arranged substantially edgewise to the axial advance so as not materially to obstruct the progress of the materials through the machine. 110
23. In a pulverizing machine a casing containing a rotatable shaft so arranged that gravity does not tend to advance the material passing through the casing, beaters carried by the shaft, and, beyond the beaters relatively fixed whirl obstructing vanes. 115
24. In a pulverizing machine a casing containing a rotatable shaft horizontally arranged, paddle-like beaters on said shaft, and wide thin whirl obstructing vanes beyond said beaters. 120
25. In a pulverizing machine a casing arranged for horizontal progress of the materials therethrough, a horizontal shaft in said casing, a set of beating paddles on said shaft, means for causing air flow through the casing toward the discharge, and whirl obstructing vanes between the paddles and the discharge. 125
26. Machine as in claim 25 and wherein the vanes are substantially flat blade-like members of width substantially not less than seven per cent of the interior diameter of the casing, and relatively thin, and set substantially edgewise to the axial advance of the materials. 130

In testimony whereof I have hereunto set my hand.

PAUL ARTHUR HIRSCH.
